J. A. Wedder, of Troy, N. Y.
Assignor to
North, Chase & North, of Philadelphia, Pa.
Letters Patent No. 911, Dated July 14th. 1857.

The schedule referred to in these Letters Patent, and making part of the same.

To all whom it may concern:

Be it known that J. A. Wedder, of the City of Troy, County of Rensselaer, and State of New York, have invented or produced a new and original design for stoves, and I do hereby declare that the following is a full and exact description of the same, reference being had to the accompanying drawings, in which

Ses. 911

- Fig: 1. represents a front plate
2. " a bottom plate
" 3. " a side plate
" 4. " a top plate
" 5. " a fancy covering for the top.
" 6. " a hearth plate.
" 7. " an air row
" 8. " a draft plate.

What I claim as my invention and desire to secure by Letters Patent, is the design and configuration of the mouldings and ornaments, as herein described, forming an ornamental design for stoves.
